United States Patent Office.

AARON CHANDLER, OF DAVENPORT, IOWA.

Letters Patent No. 88,609, dated April 6, 1869.

IMPROVED FOLDING DESK.

The Schedule referred to in these Letters Patent and making part of the same.

To all whom it may concern:

Be it known that I, AARON CHANDLER, of Davenport, Scott county, State of Iowa, have invented a new and improved Desk and Seat for Schools; and I hereby declare the following to be a full, clear, and exact description thereof, which will enable those skilled in the art to make and use the same, reference being had to the accompanying drawings, making a part of this specification, in which—

Figure 1 is a perspective view.

Figure 2 is an end view, with the seat and desk unfolded.

Figure 3 is an end view, having seat and desk folded.

Similar letters of reference indicate corresponding parts.

My invention relates to a desk and seat for schools; and

It consists in providing slots and recesses in the end pieces, by means of which a changeable portion of the top of the desk is made to assume a vertical position, and to be wholly within the space between the end pieces, and in providing a hinge for the seat, which obviates the use of an arm, or cross-piece to support it, and an improved construction and arrangement of its various parts, as will be hereinafter more fully described.

In the drawings—

A is the frame, forming the support of the top of the desk, and the back of the seat.

In its end-pieces are the slots B B', and the recesses C, and at its front edge, at a height desired for the bottom of the seat, a groove is cut, so as to leave a small upright piece, D, in which the hinge of the seat has its bearings.

B B' are the slots above referred to. They are located in the upper half of the end-pieces. B is vertical. B' is vertical at its upper end, for a short distance, when it assumes a gradual curve, which is continued nearly to its lower termination, where it strikes into a bolder curve. B are parallel, also B'.

C are small recesses, cut in the sides of slots B, which serve as resting-places for the pins on the removable top.

D is the small upright above described.

E is the seat, which has secured across its under surface, near the ends, the hinges F.

F are the hinges, whose hooked ends, lock under and behind the lower edge of the upright portion of the seat.

G is the changeable, or movable portion of the desk, which I prefer to cover with slate.

On its end-pieces two bolts, or pins are secured. These pieces fit into the slots and recesses, and are the device for lowering the removable leaf, or top, into a vertical position.

The operation of my invention is as follows:

The desk and seat being in their natural position, elevate the disengaged portion of the removable top. This slips the pins, that rest therein, out of the sockets and into the slots, slowly elevating the said top. As the pins slide in the slots, the rear portion soon reaches the termination of the slots, when the removable top will be found wholly within the space between the end-pieces.

The seat may be lifted, by its front edge, to a vertical position, and in close contact with the back. The rear edge falls into the groove between the small upright D and the back of the seat, thus making the seat secure in that situation. The removable top may be easily lifted back to its natural place, and the seat can be as conveniently lowered.

From the foregoing description, it is evident that a desk constructed substantially as mine, can be readily folded within the space occupied by the end-pieces, thus causing it to assume a compact and suitable form for transportation, and allowing at least twice the usual area to move in, while cleaning the floor, or for other purposes.

Having thus described the nature and operation of my invention,

What I claim, and desire to secure by Letters Patent, is—

The combination and arrangement of the changeable desk-cover, with its receptacle G, the slots B B', in the standards A, and pins C, substantially as and for the purpose specified.

In testimony whereof, I have signed my name to this specification, in the presence of two subscribing witnesses.

Witnesses: AARON CHANDLER.

C. W. ORMSBEE,
A. L. CHANDLER.
